[57] **CLAIM**

The ornamental design for a winter sports hat, as shown and described.

DESCRIPTION

FIG. 1 is an environmental front elevational view of a first embodiment of a winter sports hat showing our new design; FIG. 2 is a front elevational view with the rear being a mirror image thereof;

FIG. 3 is a right side elevational view with the left side being a mirror image thereof;

FIG. 4 is a top plan view thereof;

FIG. 5 is a bottom view thereof;

FIG. 6 is an environmental front elevational view of a second embodiment of a winter sports hat showing our new design;

FIG. 7 is a front elevational view thereof;

FIG. 8 is a rear elevational view thereof;

FIG. 9 is a right side elevational view with the left side being a mirror image thereof;

FIG. 10 is a top plan view thereof; and,

FIG. 11 is a bottom view thereof.

The broken line showing of the human figure in FIGS. 1 and 6 is for illustrative purposes only and forms no part of the claimed design.
